UNITED STATES PATENT OFFICE

ANDRÉ LÉON VICTOR CLÉMENT DEBRIE, OF PARIS, FRANCE

FRICITION DRIVING DEVICE CHIEFLY INTENDED FOR CINEMATOGRAPHIC APPARATUS

Application filed February 10, 1928, Serial No. 253,473, and in France February 23, 1927.

In cinematographic apparatuses the film which is driven at regular intervals by a feeding device is wound on a hub which rotates round its axis. As the film is wound on the hub, the spool thus constituted increases in diameter and consequently the circumferential speed thereon increases. As on the other hand the feeding speed of the film remains constant, the result is that if the rotation of the hub were controlled by a rigid mechanism, the film would be driven by the hub more quickly than it would be fed by the feeding device, so that it would very soon be torn. It has been proposed to remove this drawback by driving the film through a yielding device which yields sufficiently when the resistance exerted by the film passes beyond a certain value.

My invention has for its object a frictional driving device of a particularly simple kind much smaller than the similar devices and requiring no powerful springs by reason of the very manner whereby the frictional stress is exerted.

A form of execution of my invention as applied to a cinematographic apparatus is shown by way of example on appended drawings wherein:

Fig. 1 is a partly sectional side view of the device and

Fig. 2 is a cross section along line A—B of Fig. 1 with the ball bearing omitted. The hub 1 round which the film is wound is mounted loose on a shaft 2 to which is secured the inner ring 3 of a ball bearing 4 the outer ring 5 of which rotates therefore freely round shaft 2. To the side 6 of the ring 5 are pivotally secured at 7, 7' two semi-circular brake segments 8, 8' normally held apart by a spring 9 disposed in the notches 10, 10' provided at the free end of these segments. These two segments are thus pressed against the inner flange of a cylindrical drum 11 keyed to shaft 2.

A stud 12 borne by the face 6 engages a notch provided in the lateral wall 13 of the hub 1 and causes the latter to rotate.

Thus the drum 11, driven by the shaft 2 rubs on the segments 8, 8' secured to the plate

50 6 mounted on this shaft on the entire circum-

ference thereof. Therefore it is absolutely unnecessary to use for obtaining sufficient adherence, very powerful springs as is the case in devices of this kind commonly used.

It should be well understood that numerous detail modifications can be brought to the construction of the present device without altering the character of the invention. Thus for instance the ball bearing 4 might be suppressed and the ring 5 rotate directly on shaft 2. Similarly the segments 8 and 8' might bear through their inner part on the drum 11, the action of the spring 9 being in this latter case reversed. This driving device though specially studied in view of its use in cinematographic apparatuses for driving film hubs is not limited to this particular use and is adapted for the most varied applications.

What I claim is:

1. A frictional connection chiefly for cinematographic take-up mechanisms comprising a driving shaft, a reel freely mounted thereon, a part also mounted freely thereon and adapted to control the rotation of the reel, a drum keyed to the driving shaft, two semicircular segments pivotally attached by one end to the freely mounted part and the surface of which is in contact with the surface of the drum and a comparatively light spring connecting alone the free ends of the segments and adapted to press them against the drum.

2. A frictional connection for cinematographic take-up mechanism comprising a driving shaft, a reel freely mounted thereon a ball bearing the inner ring of which is keyed to the shaft and the outer ring of which is adapted to control the rotation of the reel, a drum keyed to the driving shaft, two semicircular segments pivotally attached by one end to the outer ring of the ball bearing and the surface of which is in contact with the surface of the drum and a comparatively light spring connecting alone the free ends of the segments and adapted to press them against the drum.

In testimony whereof I have signed my name to this specification.
